John D. Nease

UNITED STATES PATENT OFFICE.

CHARLES F. WRIGHT, OF AKRON, OHIO, ASSIGNOR TO THE DIAMOND MATCH COMPANY, OF CHICAGO, ILLINOIS, A CORPORATION OF ILLINOIS.

MATCH MACHINE.

Application filed November 10, 1925. Serial No. 68,160.

This invention relates to that class of match making machines wherein blocks of wood are intermittently advanced end to end, in an oblique direction, to the path of a vertically reciprocating row of cutters operative to sever successive rows of splints from the opposing portions of the blocks and stick the splints endwise into a suitable splint carrier.

10 In match machines of the class mentioned, the end of the trough in the region of the cutters, owing to its oblique relation thereto, is of tapering form, and consequently the succeeding blocks, as they are reduced by 15 the action of the splint cutters, present a triangular or wedge-like formation. The leading or thin edge of the material, as well as the larger block sections, must be held close up to the path of the cutters in order 20 to ensure the efficient action of the cutters. Heretofore a spring bar has been arranged on the trough so as to overhang and bear upon the top of the blocks, adjacent the path of the cutters, but owing to the variations 25 in height of the block sections uniform pressure of the plate thereon throughout the length of the cutting area, was not effected, and in the case of short blocks, or greatly reduced end blocks, the absence of 30 effective pressure thereon resulted in the production of imperfect splints.

The object of my invention is to provide a simple and efficient construction whereby 35 a uniform yielding pressure is efficiently applied along the forward edge of the match stock in the region of the cutters, irrespective of the varying heights or dimensions of the blocks within limits, which pressure is effectually maintained until the last match 40 splint has been cut from each succeeding block.

To this end, my invention comprises a plurality of independent spring pressure devices of novel construction arranged to overhang and bear upon the tops of the progressing blocks throughout the portions 45 thereof which are presented to the action of the cutters, as will be hereinafter described and claimed.

50 In the drawings—

Figure 1 is a sectional plan of a portion of a match machine having block-feeding mechanism equipped with pressure devices embodying my invention.

55 Fig. 2 is a transverse vertical section

through the block trough and the adjacent portion of the cutter head of the match machine, as on the line 2—2 of Fig. 1.

Fig. 3 is a plan of the yielding end portions of several of the pressure devices. 60

Fig. 4 is a view of the underside of the same.

Fig. 5 is a front end view of the said pressure devices.

Figs. 6 and 7 are views of filling pieces 65 for closing the slots in the pressure members.

Fig. 8 is a perspective view, partly in section, of two adjacent pressure members, and adjuncts. 70

Referring to the drawings, 10 designates a part of the main frame of a match machine, 11 a part of a vertically reciprocating head upon which is mounted a horizontal row of splint cutters 12, and 13 a part 75 of the splint carrier.

14 designates a horizontal trough formed or arranged on the machine frame so as to extend obliquely to the row of splint cutters, which trough is adapted to receive the blocks 80 (B) of wood and guide them to the path of the cutters, as usual. The match blocks are arranged end to end in the trough and are progressively advanced therealong to the cutters by suitable feed devices, including 85 the usual intermittently rotatable rolls 15.

In the present instance a double-feed trough whereby two parallel rows of blocks are directed to the cutters, is illustrated, but a single row feed trough may be employed, 90 if desired.

Overhanging the tapering delivery portion of the trough are two series of resilient pressure devices 16, 17 provided with depending nose portions 18 which are arranged to bear upon the tops of the two rows of blocks adjacent the front vertical surfaces that are presented to the action of the cutters. These pressure devices are constituted by the horizontal limbs 19 of angular metal sections whereof the vertical limbs 19' are bolted or otherwise secured to the back wall of the block trough, as at 20. Each of the limbs 19 is a flat plate like body slotted longitudinally a substantial distance from its free end, as at 21, to provide a plurality of resilient spring members, and the sections of each series are arranged in close relation to each other, as shown, in order that the noses 95 of the pressure members shall bear upon the 100

105

110

tops of the blocks adjacent the active path of the respective cutters.

The initial block engaging faces of the nose portions 18 of each series of pressure members are beveled and rounded, as at 22, to facilitate the free passage thereunder of the leading portions of the succeeding blocks of the respective rows, irrespective of variations in the height or size of the blocks, 10 as the latter are advanced in the cutting zone. Several of the end nose portions which bear upon the leading ends of the blocks or fragments of blocks are successively beveled, as at 23, in order to present 15 gradually reduced contact surfaces of proper size to exert efficient steadyng pressure upon the progressively small tapering ends of the stock until the last match splints have been cut therefrom by the reciprocating 20 cutters.

Preferably the overhanging terminal limb 19 of each series of sections has cut therein two spaced parallel slots 21 of different lengths which afford three narrow pressure members adapted to act with varying force 25 upon the small reduced end portions of the leading blocks or fragments of blocks of each row, and, preferably also, the outer edge of the terminal limb is corrugated to provide 30 a series of small projections X which are spaced apart correspondingly with and in alternation with the adjacent cutters so as not to obstruct the latter during their reciprocation, yet bear upon and steady the uncut 35 front portions of the reduced match stock. The overhanging limb of each of the remaining sections has cut therein a single median slot 21 which provides two pressure 40 members adapted to exert relatively greater pressure upon the larger bodies of the blocks which are presented to the cutters.

As a simple and efficient means to close the slots 21 of the respective sections, and thus prevent the accumulation therein of 45 dust and other refuse which would tend to interfere with the free independent action of the adjacent pressure members, I provide suitable filling pieces for the slots. In the case of each of the terminal sections the filling 50 piece comprises a U-shaped metal strip, the sides 24 of which are entered in the slots from the bottom, and the base or body 55 of the strip is secured to the intermediate limb, the sides terminating in tail pieces 26 which close the spaces between the adjacent nose pieces.

In the case of each of the limbs of the remaining sections the filling piece comprises a strip 27 having a base 28 which is secured 60 to the under side of one of the pair of pressure members when the strip is entered in the slot. The strip 27 similarly to the sides of the U-shaped piece, terminates in a tail-piece 29 which closes the space between the

adjacent nose pieces of the pair of pressure 65 members.

I claim—

1. In a match machine, the combination with splint-cutting mechanism including a row of cutters, and a block trough arranged 70 in oblique relation to the path of the cutters, of a series of resilient pressure sections comprising each a longitudinally slotted body having a depending nose portion adapted to overhang the trough in close relation to the 75 path of the cutters, the initial block engaging face of each of said nose portions being beveled and rounded.

2. In a match machine, the combination with splint-cutting mechanism including a 80 row of cutters, and a block trough arranged in oblique relation to the path of the cutters, of a series of resilient pressure sections comprising each a longitudinally slotted body having a depending nose portion adapted to 85 overhang the trough in close relation to the path of the cutters, several of the nose portions being successively tapering and arranged to bear upon the leading tapering portion of a block contained in the trough. 90

3. In a match machine, the combination with splint-cutting mechanism including a row of cutters, and a block trough arranged in oblique relation to the path of the cutters, of a series of resilient pressure sections 95 comprising each a longitudinally slotted body having a depending nose portion adapted to overhang the trough in close relation to the path of the cutters, and a slot filling piece arranged to permit independent 100 movement of the respective members of the slotted body.

4. In a match machine, the combination with splint-cutting mechanism including a row of cutters, and a block trough arranged 105 in oblique relation to the path of the cutters, of a pressure device comprising a metal body having parallel slots therein to provide a series of independently movable pressure members arranged to bear upon the leading thin or reduced portions of the blocks contained in the trough, and a slot filling piece 110 comprising parallel filler strips and a base portion secured to the member between the slots. 115

5. In a match machine, the combination with splint-cutting mechanism including a row of cutters, and a block trough arranged in oblique relation to the path of the cutters, of a resilient pressure member arranged 120 to bear upon the leading thin or reduced portions of the blocks contained in the trough and having forward projections in alternation with the adjacent cutters.

Signed at Barberton, in the county of 125 Summit and State of Ohio, this 6th day of November A. D. 1925.

CHARLES F. WRIGHT.
